the embodiment shown, the device is provided with a transverse wire frame member 10 which is wound in a labyrinthine fashion to form heel, shank, arch and counter parts. The wire member 10 is wound back and forth along substantially longitudinal parallel lines, looped at the ends, to conform to the contours of the heel, shank, arch and counter parts of the article of footwear 11 shown in outline in Fig. 3 and more clearly shown in Fig. 1.

UNITED STATES PATENT OFFICE

2,408,413

SUPPORTING FRAME FOR ARTICLES OF FOOTWEAR

William H. Doherty, Elmhurst, N. Y.

Application January 17, 1945, Serial No. 573,176

5 Claims. (Cl. 36—8.5)

This invention relates to supporting frames for articles of footwear.

The principal object of the invention is to provide a supporting frame for an article of footwear, said frame having interconnected heel, shank, arch and counterparts.

A further object is to provide a supporting frame of the character described which would stiffen the article of footwear and yet yield sufficiently to endow the article of footwear with a 10 desired measure of flexibility.

Still another object of the invention is the provision of a frame of the character described upon which a plastic or rubber sole, shank and heel may be fabricated.

A still further object is the provision of an article of footwear which would support substantially the entire foot, said article of footwear being intended to be used by persons having weak arches and other foot conditions.

Preferred embodiments of the invention are shown in the accompanying drawings in which—

Fig. 1 is a perspective view of a shoe provided with a supporting frame of the character herein described and claimed;

Fig. 2 is a transverse vertical section of said shoe on the line 2—2 of Fig. 1;

Fig. 2a is a fragmentary perspective view of an interlaced portion of said supporting frame;

Fig. 2b is a side elevational view partly in section of a fragment of the wire member which is wound to form the supporting frame herein described and claimed, said view being of a sharp bend in said wire member showing a sleeve fitted over said wire member at said bend;

Fig. 2c is a view similar to that of Fig. 2b of another portion, being drawn through a supporting metal plate by which the frame is affixed to the shoe;

Fig. 2d is a view similar to that of Fig. 2b showing a spirally wound wire sleeve on the bend of the wire member;

Fig. 3 is a perspective view of the wire frame herein described and claimed;

Fig. 4 is a bottom view of said frame showing how it is affixed to a supporting plate;

Fig. 5 is a longitudinal vertical section of the device shown in Fig. 4;

Fig. 6 is a fragmentary perspective view of another method of affixing the wire frame to the supporting plate;

Figs. 2a, 2b, 2c and 2d are variants which may be incorporated into the embodiment shown in Figs. 1, 2, 3, 4 and 5. Fig. 6 is a modification of the embodiment shown in Figs. 1, 2, 3, 4 and 5.

Referring now to Fig. 1, it will be seen that the preferred embodiment of the invention comprises a unitary wire frame member 10 which is wound in labyrinthine fashion to form heel, shank, arch and counter parts. It will be seen in said Fig. 1 that the wire member 10 is wound back and forth along substantially longitudinal parallel lines looped at the ends, to conform to the contours of the heel, shank, arch and counter parts of the article of footwear 11 shown in outline in Fig. 3 and more clearly shown in Fig. 1.

Referring now to Fig. 3, it will be seen that the preferred embodiment of the invention comprises a unitary wire frame member 10 which is wound in labyrinthine fashion to form heel, shank, arch and counter parts. It will be seen in said Fig. 3 that the wire member 10 is wound back and forth along substantially longitudinal parallel lines looped at the ends, to conform to the contours of the heel, shank, arch and counter parts of the article of footwear 11 shown in outline in Fig. 3 and more clearly shown in Fig. 1.

The heel part of the frame member 10 comprises upper and lower parts 12 and 13, respectively, which are spaced a predetermined distance apart, and a breast part 14 immediately integral with the lower part 13. The breast part 14 serves as a resilient spring support for the lower part 13.

The counter part 15 of the frame member 10 is held in place by means of a band 16 which curves around the back of the article of footwear and which is looped around and thereby affixed to the counter part 15.

Slidably mounted on the arch part 17 of the frame member 10 are sleeve members 18 whose function will hereinafter appear.

Affixed to the shank part 19 by means of rivets 20 is a shank plate 21 which serves to stiffen the frame member 10 and also helps fix said frame member to the article of footwear.

The shank plate is shown most clearly in Figs. 1, 4 and 5. It will be seen in Fig. 5 that rivets 20 not only affix the shank plate to the frame member 10 but also affix both the shank member and the frame member to the article of footwear proper and, more particularly, to its inner sole and welt members 22 and 23, respectively. It will also be seen in Fig. 5 that the heel contacting part 24 of the shank plate is provided with longitudinal slits 25 and horizontal waves 26. The purpose of this construction is to endow said shank member with the properties for added resilience and strength. Said heel contacting part 24 of the shank member is welded to the breast part 14 of the heel of the frame member 10.

Corresponding to sleeves 18 on arch 17 of the frame member 10 are tubular members 30 and 31, respectively, shown in Figs. 2b and 2d. Tubular member 30 is made of a plastic material. Tubular member 31 comprises a flexible spring wound spirally. It will be noted in Figs. 2b, 2c and 2d that these tubular members are applied to the wire comprising frame member 10 at the sharp bends in said wire member. The purpose of this, as well as the purpose in the use of sleeve members 18, will shortly appear.

To properly space the labyrinthine lines into which the frame member is wound, tapes 32 are woven into the frame member to form a web, as is clearly shown in Fig. 2a.

The counter 15 and arch 17 of the frame member 10 are disposed between the inner and outer layers of leather or other material which comprises the upper member 9 of the article of footwear 11. Stitches 18a affix the inner and outer layers to each other and also assist in properly spacing sleeves 18. The heel and shank members of the frame member 10 are embedded in the plastic or rubber composition heel and shank members of the article of footwear. This will be seen in Fig. 2 where the shank part of the frame member 10 is shown embedded in the composition shank member 8 of the article of footwear 11. As has previously been indicated, the frame member and the shank plate to which it is affixed are both fastened to the inner sole and welt members of the article of footwear by means of rivets.

The purpose of sleeves 18 and tubular members 30 and 31 now becomes clear. Wherever it is desired to provide for relative movement between the frame member 10 and the article of footwear proper 11, either the sleeves 18 or the tubular members 30 or 31 are applied to said frame member. Relatively rigid contact is made between said sleeves and tubular members on the one hand, and the article of footwear proper on the other. But since said members are slidably mounted on the frame member 10, relative flexibility between said frame member and said sleeve and tubular members and hence between said frame member and the article of footwear proper, is thus provided for.

The embodiment above described is but a preferred embodiment of the invention and a number of modifications and variations may be introduced therein without departing from the basic principles of the invention. For example, instead of making the frame member 10 out of a single length of wire wound back and forth in labyrinthine fashion above described, a number of shorter lengths of wire 40 might be used. In such case, instead of being looped at the forward and rear ends of the frame member, they would terminate at said points. Instead of being riveted, therefore, to the shank plates as above described, they would be affixed thereto by means

of retaining brackets 41 which themselves are welded to the shank plate. The frame member 10 should preferably be made of spring metal wire but it may be made of other resilient material as well, such as some of the new plastic materials which have recently been developed.

I claim:

1. A supporting frame for an article of foot-wear, said frame comprising a unitary wire member wound in labyrinthine fashion to form interconnected heel, shank, arch and counter parts.
2. A supporting frame for an article of foot-wear, said frame comprising a unitary wire member which is wound back and forth along substantially longitudinal, parallel labyrinthine lines to conform to the contours of the heel, shank, arch and counter parts of said article of footwear.
3. An article of footwear including a supporting frame carried thereby, said frame comprising a unitary wire frame member wound in labyrinthine fashion to form interconnected heel, shank, arch and counter parts, sleeves slidably mounted on said frame where relative movement between the frame and the article of footwear is found desirable, and means for affixing said frame and said sleeves to said article of footwear.
4. An article of footwear having a supporting frame affixed thereto which comprises a shank plate, a wire frame member affixed to said shank plate, and sleeves slidably mounted on said wire frame member where relative movement between the unitary wire member and the article of footwear is required, said wire frame member comprising a unitary wire member wound in labyrinthine fashion to form interconnected heel, shank, arch and counter parts.
5. In an article of footwear having composition heel, shank and sole members, a supporting frame comprising a shank plate, a wire frame member affixed to said shank plate and sleeves slidably mounted on said wire frame member where relative movement between said wire frame member and the article of footwear is desired, said wire frame member consisting of a unitary wire member wound in labyrinthine fashion to form interconnected heel, shank, arch and counter parts, said shank plate and said heel and shank parts of the wire frame member being embedded in the composition heel and shank members of the article of footwear.

WILLIAM H. DOHERTY.
